UNITED STATES PATENT OFFICE.

BLASIUS BEGUZ, OF FEISTRITZ, AUSTRIA-HUNGARY.

WIRE-DRAWING MACHINE.

SPECIFICATION forming part of Letters Patent No. 413,889, dated October 29, 1889.

Application filed June 27, 1889. Serial No. 315,693. (No model.)

To all whom it may concern:

Be it known that I, BLASIUS BEGUZ, a subject of the Emperor of Austria-Hungary, residing at Feistritz, in the Duchy of Carinthia 5 and Empire of Austria-Hungary, have invented certain new and useful Improvements in Wire-Drawing Apparatus; and I do hereby declare the following to be a full, clear, and exact description of the invention, such as 10 will enable others skilled in the art to which it appertains to make and use the same.

This invention relates to that description 15 of wire-drawing machines in which in a single operation the wire is drawn out several degrees of fineness by causing a series of drums to draw the wire successively through a series of dies. With those machines that have heretofore been used for this purpose a confusion 20 is apt to take place among the several lengths of wire, so that the drawing operation has to be frequently interrupted, thereby reducing the rate of production of the machines.

According to the present invention the 25 above inconvenience is obviated by arranging between the drawing-cylinders and the dies intermediate guide rollers or pulleys, so that the wire passing from the die to the drawing-cylinder is made to pass over such intermediate rollers and then again over the 30 cylinder, from which it then passes to the next die. By this means a sufficient interval is provided between the separate contiguous wires passing through the dies to effectually prevent any entanglement thereof. The 35 drawing-cylinders may for this purpose be either cylindrical or conical, with suitable grooves or divisions, or they may be smooth, in which latter case the intermediate guide-rollers receive a longitudinal movement in 40 the direction of the axis of the drawing-cylinder in order to prevent any wear of the surface of the latter. The axes of the intermediate rollers are furthermore provided with devices which counteract the tensional strain 45 of the wire and prevent the intermediate roller from bearing against the drawing-cylinder.

The accompanying drawings show various 50 arrangements for carrying out the above-described invention.

Figures 1 and 2 show, respectively, a dia- 55 grammatic elevation and plan of the arrange-

ment with the drawing-cylinder. Fig. 3 is a side view, and Fig. 4 is a plan, showing a modification of the machine provided with a 55 conical drawing-cylinder. Fig. 5 is a side view, and Fig. 6 is a plan, showing a modification of the machine provided with a smooth ribless drawing-cylinder. Fig. 7 is a side view, and Fig. 8 is a plan, showing a modification of the machine having a drawing-cylinder provided with a series of disks or ribs for separating the loops of wire. Fig. 9 is a side view, and Fig. 10 is a plan, showing a modification of the machine provided with 60 drawing-cylinders mounted on vertical shafts. 65

In Figs. 1 and 2 the wire passes from the reel F, which may dip into a pickling-bath, over the guide-roller C, which has angular grooves C', to the die fixed in the frame B, 70 from which it passes to the drawing-cylinder D, driven by the main shaft of the machine, and which dips in a suitable manner into the bath Z, filled with pickling-liquor. This drawing-cylinder D is also formed with a series of projecting ribs, flanges, or circumferential partitions, which form angular grooves D', and the wire passes from one of these grooves D' to the intermediate guide-roller E, which, as before described, forms the main 75 feature of this invention. This roller is carried loose on an axis situated parallel to the axis of the drawing-cylinder D. These intermediate guide-rollers E also have angular grooves E', and several of these rollers being 80 situated side by side loose on their common axis it will be seen that they may revolve in contrary directions independently of each other. From these intermediate guide-rollers the wire again passes over the drawing- 85 cylinder D, where it enters a groove D', next to the groove from which it before passed to the guide-roller. In this groove it is carried through the pickling-liquor, and thence over the guide-roller C to another drawing-die. 90 From this it again passes to the drawing-cylinder D, and thence over the intermediate guide-roller E, and so on as many times as there are dies through which the wire is to be drawn. Lastly, the wire passes as a finished 95 product from the drawing-cylinder onto the winding-drum A, which is driven direct from the driving-shaft. In order to neutralize the bending strain produced by the wire tending 100

to force the drawing-cylinder D and the intermediate guide-roller E toward each other, the axis of the latter carries one or more contact-rollers G, which bear against a corresponding surface on the cylinder, and thus prevent any contact between the intermediate roller and the drawing-cylinder. As in this case each wire runs in a separate V-groove on the drawing-cylinder, no confusion or entanglement of the several coils of wire during the process of drawing can occur. The axes of the drawing-cylinder D and intermediate guide-rollers E are in this case assumed to be supported on each side; but in order to facilitate the coiling on of the wire in the first instance these axes may be arranged in such a way that they are corbeled out. The bearings are both situated at one of the frontal sides of the cylinder and guide-rollers, and have the driving-gear for the drawing-cylinder situated between them.

The arrangement shown by Figs. 3 and 4, respectively in elevation and plan, chiefly differs from the foregoing in that the drawing-drum D, with its angular groove D', is not cylindrical, as before, but conical or tapering. In this case the axis on which are mounted the intermediate guide-rollers E and the supporting-roller G is not parallel to that of the drawing-drum, but parallel to the conical surface thereof. The course taken by the wire is the same as before, with the single difference that before it passes from the drawing-drum over the guide-roller C to the next drawing-die it is led over the lower guide-roller H, dipping into the pickling-liquor contained in the vessel Z below, so that the wire before each passage into the next die is carried through the pickling-liquor; also, in this case the free support of the axes of the drawing-drum and the intermediate guide-rollers referred to in the previous arrangement may be adopted.

In the arrangement shown at Figs. 5 and 6 the drawing-drum is formed without the before-described angular groove, being made perfectly smooth and cylindrical. In order also in this case to prevent entanglement of the several windings of the wire, the intermediate guide-rollers carried on an axis parallel to that of the drawing-drum D are provided each with two grooves E'. Over one of these grooves the length of wire is passed, which, coming from the drawing-die, passes onto and round the drawing-drum, so that this groove serves to guide the wire always in one direction. The second groove of each intermediate guide-roller serves to guide the wire before it passes a second time round the drawing-drum from which it then passes over the guide-roller C to the next drawing-die. By this arrangement no entanglement of the windings of wire can take place. In order in this arrangement to prevent any wear of the smooth cylindrical drawing-drum, for which generally very hard material is used,

the axis on which the intermediate guide-rollers E are mounted receives a slight reciprocating motion in the longitudinal direction, so that by this means also the wires passing over the drawing-drum D receive a continuous to-and-fro movement in the direction of the axis of the drum, thereby causing any wear to take place uniformly on the entire surface of the drum in the longitudinal direction. The means for imparting this to-and-fro motion to the axis of the intermediate guide-rollers E may be variously modified.

In the drawings is shown, by way of example, an inclined disk or cam I, which is actuated by the drawing-drum or any other rotating part of the machine, and which bears against a suitably-formed head M, fixed on the end of the axis of the intermediate guide-rollers E, thereby imparting to such axis a motion in one direction, while the return motion is effected by a spring K.

In Figs. 7 and 8 is shown an arrangement similar to that just described, with the principal difference that, in order to still further prevent any entanglement of the wires, there are provided on the cylindrical drum D thin partition-disks D², which are situated between each two coilings of the wire on the drum, so that these partition-disks also keep separate those windings of the wire that are not led round the intermediate guide-rollers E; also, in this case a reciprocating motion is imparted to the intermediate guide-rollers, and consequently, also, to the wires in the direction parallel to the axis of the drawing-drum.

The above-described arrangement of the bearings for facilitating the winding on of the wire can also be adopted in this arrangement in such manner that the apparatus is provided with two symmetrically-arranged drawing-drums, the space between the two being utilized both for the driving-gear of the drawing-drums, as also for the arrangement for imparting a reciprocating motion to the axis of the guide-rollers and for the bearings of the axis.

Figs. 9 and 10 show an arrangement in which the drawing-drums are mounted on vertical axes, those before described being assumed to be horizontal. With this arrangement the two symmetrically-arranged drawing-drums are formed conical, and are also provided with angular grooves, which are not shown on the drawings on account of the smallness of the scale. The intermediate guide-rollers E are each mounted on a separate axis, all the axes of the guide-rollers belonging to one drum being mounted in a frame N, which is connected to the two supports O O' of the bearings for the drawing-drum D, so that a line drawn through the center of all the intermediate guide-rollers lies parallel to the conical surface of the drawing-drum instead of to its axis. The guide-rollers C, having angular grooves, are formed in this case with varying diameters. The

wire passes from the reel F over small guide-rollers *r* onto the first lower groove of the right-hand drawing-drum D. It then passes over the smallest of the guide-rollers C, at the same time dipping into the vessel Z, containing pickling-liquor, and passes thence to the first drawing-die situated in the left-hand frame B. From there it passes to the lower groove of the left-hand drawing-drum D, and passes around the same and around the intermediate guide-rollers E twice. It is then led over the second smallest guide-roller C of the front set, and in passing around the same dips into the pickling-liquor, from which it passes to the drawing-die situated in the right-hand frame B. From there it passes to the second groove of the right-hand drawing-drum D. After having passed twice around the same and around the intermediate guide-roller E the wire passes over a guide-roller C, through the pickling-liquor, and again to the left-hand drawing-drum D, and so on until it has passed through all the several drawing-dies. This motion of the wire is indicated on the drawings by the numerals 1 to 22. The two symmetrical drawing-drums D, acting together, are driven by one and the same shaft F and bevel-gear Q Q.

What I claim is—

30 1. In a wire-drawing machine, the combination, with a revoluble drawing-cylinder, of a series of guide-rollers journaled on a shaft, a series of dies for gradually reducing the wire arranged between the said rollers and the cylinder, and a series of intermediate guide-rollers journaled between said dies and the cylinder for the wire to pass around, substantially as set forth.

2. In a wire-drawing machine, the combination, with a revoluble drawing-cylinder provided with a series of circumferential projecting ribs for separating the loops of the wire, of a series of guide-rollers journaled on a shaft, a series of dies arranged between the said rollers and the cylinder, and a series of

intermediate guide-rollers journaled between said dies and the cylinder for the wire to pass around, substantially as set forth.

3. In a wire-drawing machine, the combination, with a revoluble conical drawing-cylinder provided with a series of circumferential projecting ribs for separating the loops of the wire, of a series of guide-rollers journaled on a shaft, a series of dies arranged between the said rollers and the cylinder, and a series of intermediate guide-rollers journaled between said dies and the cylinder parallel with the surface of said cylinder for the wire to pass around, substantially as set forth,

4. In a wire-drawing machine, the combination, with a revoluble drawing-cylinder, of a series of guide-rollers journaled on a shaft at a short distance from said cylinder, and one or more rollers of greater diameter than said guide-rollers journaled on the said guide-roller shaft and bearing against the surface of the cylinder for relieving the shaft from bending strain, substantially as set forth.

5. In a wire-drawing machine, the combination, with a revoluble drawing-cylinder, of a longitudinally-reciprocating shaft and a series of guide-rollers for the wire to pass around, journaled on said shaft and partaking of its reciprocating motion, substantially as and for the purpose set forth.

6. In a wire-drawing machine, the combination, with a revoluble drawing-cylinder, of a shaft parallel with the surface of said cylinder, a series of grooved guide-rollers journaled on said shaft, and a cam and a spring for imparting a longitudinal reciprocating motion to said shaft and guide-rollers, substantially as and for the purpose set forth.

In testimony whereof I affix my signature in presence of two witnesses.

BLASIUS BEGUZ.
